UNITED STATES PATENT OFFICE

AMADEUS G. DALMAS, OF OAKLAND, CALIFORNIA

MANICURING DEVICE

Application filed July 27, 1931. Serial No. 553,331.

The invention relates to a hand device for manicuring finger nails.

An object of the invention is to provide a device of the character described in which will be combined in a single unit all of the various tools and appliances necessary or desirable for effecting the different manicuring operations.

Another object is to provide a device of the character described by which the different manicuring operations may be effected in a very efficient manner.

The invention possesses other objects and features of advantage, some of which, with the foregoing, will be set forth in the following description of the preferred form of the invention which is illustrated in the drawing accompanying and forming part of the specification. It is to be understood, however, that variations in the showing made by the said drawing and description may be adopted within the scope of the invention as set forth in the claims.

Referring to the drawing:

Figure 1 is an end view of the device of my invention.

Figure 2 is a side elevation of the device, with a portion broken away to disclose some of the inner construction.

Figure 3 is an end view of the device viewed from the end opposite to that shown in Figure 1.

Figure 4 is a bottom view of the device.

Figure 5 is an enlarged fragmentary side view of the file surface provided on the inner side of one of the arms of the device.

Figure 6 is an edge view of the portion shown in Figure 5.

Figure 7 is a transverse sectional view of another arm of the device showing the form of file surface provided thereon.

Figure 8 is a view similar to Figure 7 showing a modified form of one of the file members.

As illustrated in the drawing, the device of my invention comprises a pair of arms or plates 2 and 3 which preferably normally diverge outwardly and are formed together with a connecting portion 4 as integral parts of a single strip of spring metal. Extending

angularly from the ends 6 of the arms are shearing plates 7 which as shown in Figure 1 are sharpened on their free edges and arranged for cooperation so as to function as a scissors when the arms are moved toward each other. Similarly, at the other ends 8 of the arms are provided curved shearing extensions 9 which are arranged for cooperation so as to provide a nail clipper, the shearing edges being as indicated in Figure 3, normally spaced and of such form that upon inward movement of the arms the nails may be severed by a shearing rather than a slicing action. It will be evident that since the device is formed of a springy material, alternate pressure and release of the arms will effect the necessary movement of the arms to cause the cutting operation. It will now be seen that without the addition of separate parts there is effectively provided both a nail clipper and a scissors for cutting the nails and the skin thereabout. As a means of cutting the cuticle at the base of the nails the corner extremities of the arms are sharpened and curved in conformity with such cuticle portion.

Means are provided for permitting with the use of my device the filing of the nails in a particularly effective manner with little effort or skill upon the part of the user. Provided on the inner side of the arm 2 is a file surface 11, the teeth 12 of which extend lengthwise of the arm from practically one end thereof to the other. In using this file, the finger is inserted between the two arms so that the front of the finger may rest on the outer edge 13 of the arm 3 with the nail in engagement with the file surface; the device is then moved so that the arm 2 moves across the nail while the finger is rolled slightly to give the proper curvature to the edge of the nail. Preferably the teeth are inclined away from the outer edge of the arm so that the filing is effected as the device is moved from the nail. It is to be noted that since the filing is done with the device fully crumpled on the finger, the edge of the nail will be rounded in cross section in the approved manner.

Provided on the inner side of the arm 3 is a file surface here shown comprising sections

100

- 15 and 16 extending from the center of the arm to the ends 6 and 8 respectively, and having teeth which extend at right angles to the teeth on the arm 2. As will be clear from Figure 6, the teeth of section 15 are inclined toward the end 6 while the teeth of section 16 are inclined toward the adjacent end 8. In using this file, the finger is placed between the arms as in the use of the file 11, but in reversed relation, that is, with the front of the finger against the edge of arm 2 and the nail against one or other of the sections 15 and 16. Each of the sections is preferably utilized for filing one half of a nail, each section at the start of the filing operation being usually placed in engagement with the middle of the nail and then moved toward the extremity of the nail lying near the outer end of the section.
- 20 As an effective means of shaping or trimming down the edge of the nail, I provide in one of the arms, preferably near and along the outer edge thereof, a groove 17 on the bottom of which is formed a suitable filing surface 18. In the use of the file, the nail is placed within the groove and then reciprocated over the file surface, the nail being guided during the filing operation by the sides of the groove. Along the edge 13 of the arm 3 I preferably provide an undulated surface whereby such edge may be inserted under the nail and drawn therealong to remove any foreign matter that may have collected on the skin adjacent thereto.
- 25 30 35 In order to complete the usual manicuring operation, I affix on the outer side of the connecting portion 4 of the device, a brush 19 having bristles 21 suitable for polishing the nails. Likewise a narrow row of bristles 22 extends downward along the outer side of one of the arms. The latter arrangement is effective for cleaning under the nails, since the arm may be used as a guide for the fingers when they are being drawn across the arm with the bristles entered under the nails.
- 40 45 In Figure 8 I have shown a somewhat modified form of the filing medium as used on the arms. In this embodiment, a replaceable filing element such as an emery board 23 is removably held on the inner side of an arm by means of suitable tongues 24 punched inwardly from the arm.
- 50 55 It will now be evident that the device of my invention is well adapted to the accomplishment of the objects hereinabove referred to.
- I claim:
- 60 65 70 75 80 85 90 95 100 105 110 115 120 125 130
1. In a manicuring device, a plate having a filing surface provided on a side thereof, a finger guide in opposed relation to said file surface and spaced therefrom to permit of a finger being inserted therebetween, and means securing said plate and guide together.
  2. In a manicuring device, a plate having a filing surface provided on a side thereof, a

plate secured to said first plate in opposed and spaced relation to said surface and having an edge portion arranged to serve as a guide for the finger when the nail thereof is in engagement with the file, said file comprising independent sections with the teeth of one section inclined reversely of the teeth of the other section.

3. In a manicuring device, a pair of plates fixed together in spaced relation for the insertion of a finger therebetween and having filing surfaces on the opposed inner sides of the plates, an edge portion of each plate arranged for guiding the finger when the nail thereof is in engagement with the file of the other plate.

4. In a manicuring device, a plate, a filing element replaceably held on a side thereof, and a finger guiding member fixed to said plate in spaced and opposed relation to said element.

5. In a manicuring device, opposed plates secured together at their ends in spaced relation and arranged for movement to and from each other, cooperating shearing members extending from opposed side edges of said plates, and a filing element on the inner side of one of said plates.

6. In a manicuring device, opposed outwardly diverging plates secured together at their inner edges and arranged to be moved to and from each, a filing means on their sides, cooperating shearing members at each of the opposite ends of said plates, a portion of a plate being sharpened and curved to serve as a cuticle cutter, one of said plates having a grooved portion with a filing surface at the base thereof, the edge of one of said plates being undulated and arranged for insertion under the nail, a nail polishing brush at the portion of the device connecting said plates, and a nail cleaning brush extending downwardly along a side of one of said plates.

In testimony whereof, I have hereunto set my hand at Oakland, California, this 15th day of July, 1931.

AMADEUS G. DALMAS.
